UNITED STATES PATENT OFFICE.

JOHN McGAVIN AND E. CRAWFORD SANDFORD, OF NEW YORK, N. Y.

MANUFACTURE OF OIL-CLOTH.

SPECIFICATION forming part of Letters Patent No. 293,487, dated February 12, 1884.

Application filed January 10, 1884. (No model.)

To all whom it may concern:

Be it known that we, JOHN McGAVIN and E. CRAWFORD SANDFORD, citizens of the United States, residing at New York, in the county 5 and State of New York, have invented new and useful Improvements in the Manufacture of Oil-Cloth, of which the following is a specification.

This invention relates to a new method of 10 coloring and printing oil-cloth, and to the improved apparatus used for this purpose, the novel features being pointed out in the following specification and illustrated in the accompanying drawings, in which—

15 Figure 1 represents a longitudinal vertical section of the apparatus. Fig. 2 is a plan or top view of the same.

Similar letters indicate corresponding parts.

In the manufacture of oil-cloth as heretofore conducted, the oil-cloth is first coated 20 with the ground color by passing the same through a suitable machine, and then the required ornaments are printed thereon, which operation is usually performed by means of 25 engraved wooden blocks. Our method consists in coating and printing the cloth in one continuous operation. For this purpose we use an apparatus such as represented in the accompanying drawings, in which the letter 30 A designates the frame, on one end of which is mounted the spindle B. On this spindle is wound the cloth to be colored and printed. Above the spindle B is situated the box C, which contains the ground color, and which 35 is provided with a gate, *a*, and with a doctor, *b*. When the gate is opened and the cloth is drawn out from the roller beneath the box C, the color which discharges from this box is 40 spread over the surface of the cloth by the doctor *b*, and the surplus color is forced back toward the box, so as to give an even and uniform surface to the layer of color which remains on the cloth. The cloth is then carried

through between the printing-cylinder D and the pattern-cylinder E, which are mounted in 45 the frame A and geared together, so that they revolve with a uniform superficial velocity. The pattern-cylinder is supplied with the required color by the color-roller F, which dips into the color contained in the fountain G, and 50 which is geared together with said pattern-cylinder, so as to revolve with the same superficial velocity.

H is a drag-roller, which serves to draw the cloth along after the same has passed through 55 between the printing-cylinder and the pattern-roller. Said drag-roller is covered with wire-cards, or equivalent material capable of producing the desired effect upon the cloth. By 60 these means the operation of coloring and printing oil-cloth can be effected in a comparatively short time, and various beautiful effects can be produced.

It is evident that additional pattern-cylinders may be used. 65

What we claim as new, and desire to secure by Letters Patent, is—

1. In the manufacture of oil-cloth, the method herein described, consisting in coating and printing the cloth in one continuous operation. 70

2. The combination, substantially as hereinbefore described, of the color-box and doctor with the printing-cylinder and color-roller.

3. The combination, substantially as hereinbefore set forth, of the color-box and the 75 doctor with the printing-cylinder, the pattern-cylinder, the color-roller, and the drag-roller.

In testimony whereof we have hereunto set our hands and seals in the presence of two sub- 80 scribing witnesses.

JOHN McGAVIN. [L. S.]
E. CRAWFORD SANDFORD. [L. S.]
